SULPHATE PULP PROCESS

Daniel J. Young, Tacoma, Wash., assignor to
 Young-Whitwell Gas Process Company,
 Tacoma, Wash.

Application September 15, 1937, Serial No. 163,973

3 Claims. (Cl. 92—9)

The invention relates to improvements in the process of treating wood and like cellulosic material for the formation of pulp, and more particularly to the elimination of objectionable odors which are especially characteristic of the manufacture of pulp by the sulphate process. It is known that the gases resulting from sulphate pulp manufacture contain certain non-condensable components having an extremely nauseating odor and consisting largely of combustible mercaptans and the like.

In the ordinary method of manufacture of sulphate pulp the cellulosic materials to be treated (usually wood chips) together with the usual chemicals are placed in the digester and steam is admitted at or near the bottom of the digester until the pressure within the digester reaches about 125 to 135 pounds with the consequent temperature within the digester from 350° to 400° F. This condition may be maintained for a period of about one and one-half hours and is known as the "cook". When the pulp has been sufficiently cooked the steam is turned off, the bottom of the digester is opened and the pulp is discharged into a closed tank generally known as the blow pit, in which tank the liquor containing the chemicals and the pulp are held and the excess steam and gases resulting from the cook are carried away and condensed, the non-condensable gases being then usually discharged at the base of the boiler stack, coming out of the top of the stack with the gases from the boiler.

As the process is now carried out a large amount of air is taken in with the gases and steam so that the gas as admitted to the bottom of the stack is practically all air though containing the mercaptans. These mercaptan gases being combustible, many efforts have been made to burn them at this time but due to the extent of dilution with air such attempts have proved unsuccessful.

The total amount of mercaptans produced during the process is relatively small, that produced in a digester approximately ten feet in diameter and sixty feet high, which was studied in connection with the present invention, being about 100 to 150 cubic feet each time the digester is blown, a blow taking place about once an hour. However, when these gases are allowed to pass unburned into the atmosphere the objectionable odor may be observed for a distance of many miles. The nuisance is so great that in many communities sulphate plants are not permitted to operate simply on account of the odor although from a business standpoint such a plant

would be a distinct asset to the community provided the objectionable odors resulting therefrom could be eliminated.

The primary object of the present invention is to withdraw the objectionable gases directly from the digester before they have become diluted with air and to preferably burn them or otherwise dispose of them in a manner which is not objectionable. The ordinary equipment may be maintained practically without change, it being only necessary to add a condenser communicating with the top of the digester through a valve connection, the condenser being equipped with a gas offtake leading to a gas holder or the like to which the non-condensed vapors are conveyed and from which they may be withdrawn for burning or other unobjectionable disposal.

The invention will be more readily understood by reference to the accompanying drawing in which there is illustrated somewhat diagrammatically a sulphate pulp digester of conventional type equipped with the improved connections whereby the malodorous gases may be withdrawn and disposed of without pollution of the atmosphere.

Referring to the drawing the reference numeral 10 denotes a digester of any desired type being approximately 10 feet in diameter and 60 feet high although obviously not limited to these proportions. The digester is filled with wood chips and chemicals to a level 11 at approximately two-thirds the height of the digester. The steam inlet 12 may be provided near the bottom of the digester and a removable cap 13 is shown at the top to permit charging of the digester and also for the preliminary discharge of air prior to the digestion proper. The digester is provided with a bottom 14 through which the digested materials may be discharged into a blow pit 15 of conventional form. The blow pit is shown as provided with an offtake 16 for gas and steam leading to a condenser 17 provided with a liquid outlet 18 and a gas outlet 19. Ordinarily the gases passing from the outlet 19 are so diluted with air that it is impossible to burn the mercaptans contained therein.

According to my invention an outlet pipe 20 for gas and steam is provided at the top of the digester, such outlet being preferably provided with a valve 21. The pipe 20 is preferably of relatively small diameter so as not to interfere with the pressure which is maintained within the digester. The pipe 20 leads to a condenser 22 which may be of the surface type or of the type commonly used in gas plants and referred to

as the scrubber. The condenser is equipped with a liquid outlet pipe 23 and with an offtake pipe 24 for non-condensable gases. These gases include the mercaptans in sufficient quantity for combustion. The pipe 24 communicates with a gas holder 25 which may be of conventional type and which is shown as equipped with an offtake 26 controlled by a valve 27. The offtake 26 may lead to a suitable burner where the mercaptans or other malodorous gases are disposed of instead of being discharged directly into the atmosphere.

According to my method after the digester has been charged steam is admitted at the bottom 15 of the digester and the cap 13 is left open for a short time until the air has been swept out of the digester by the steam. The cap 13 is then closed thereby maintaining the digester air-tight. Further steam under pressure is admitted to the 20 digester and continues to flow in sufficient amount to maintain the pressure in the digester from 125 to 135 pounds more or less. As this steam flows upward through the pulp and liquor it will force the steam and gases which are above the 25 liquor out through the pipe 20 into the condenser 22 where the steam and other condensable portions will be separated from the non-condensable gases, which are being conducted to the gas holder from which they may be periodically 30 withdrawn for burning. According to this method no air will be present with the gases and they can be satisfactorily burned. During the cooking process the valve 21 may be opened either intermittently or constantly. If desired two or 35 more digesters may be used in battery, the steam and gases from one digester passing into a second one thus more efficiently utilizing the heat of the steam.

After the digesting process is completed the 40 pulp and liquor from which the malodorous gases have been substantially completely driven will be discharged into the blow pit in the usual manner and any gases remaining therein will be passed to the condenser 17. Since the mercaptans have been eliminated during the digesting 45 period there is no objection to passage of the non-condensable gases through the outlet 19 directly to the atmosphere, since such gases are substantially wholly air.

50 The invention has been described in detail with reference to a particular form of apparatus but it will be understood that many different combinations of operation may be employed without departing from the spirit of the invention which 55 consists briefly in withdrawing the gas and sufficient steam to carry the gas, from the digester during the digesting operation, condensing the steam from the gas and conducting the gas to a place where it may be burned, care being exercised to prevent an excess of dilution by air, the 60 gas being at all times kept in closed containers

or pipes until it is burned, thereby preventing malodorous gases from escaping into the atmosphere.

I claim:—

1. The improvement in the process of treating sulphate cellulosic pulp contained in a digester, for the purpose of avoiding contamination of the atmosphere with malodorous sulphur containing gases; which comprises sweeping out substantially all of the air from the digester prior to the commencement of the cooking process, then admitting to the digester steam under pressure to perform the cooking operation, and during the cooking stage withdrawing the resulting gases and vapors from the digester substantially free from air, separating the condensable from the non-condensable portions containing the malodorous constituents without introduction of air, and burning said non-condensable portion. 10

15 2. A combined process for treating sulphate cellulosic pulp contained in a digester and disposing of the resulting malodorous sulphur containing gases without contamination of the atmosphere; which comprises sweeping out substantially all the air from the digester prior to the cooking process, then cooking the pulp and during the cooking process and prior to discharging the pulp from the digester, withdrawing the gases and vapors resulting from the cooking operation substantially free from air, separating the condensable portions from the non-condensable portions containing the malodorous constituents without introduction of air, and burning said non-condensable portion whereby the malodorous gases are destroyed. 30

35 3. A combined process for treating sulphate cellulosic pulp contained in a digester, and for eliminating the resulting malodorous sulphur containing gases without contaminating the atmosphere; which comprises conducting the treatment of the pulp in the digester in two distinct stages, the first of which comprises sweeping out substantially all of the air from the pulp prior to the commencement of the cooking process, and the second of which comprises cooking the pulp 40 from which air has been driven off while avoiding the admission of further air, and during the cooking process and prior to discharging the pulp from the digester, withdrawing the gases and vapors resulting from the cooking operation from the top of the digester, separating the condensable from the non-condensable portions containing the malodorous constituents without introduction of air, and burning the combustible constituents of said non-condensable portion where- 45 by the malodorous gases are destroyed; the pulp being discharged from the bottom of the digester after the gases and vapors have been withdrawn. 50
